UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

NONSATURATING INDUCTION RELAY.

Application filed January 22, 1923. Serial No. 614,331.

To all whom it may concern:

Be it known that I, CHESTER I. HALL, a citizen of the United States, residing at Fort Wayne, county of Allen, State of Indiana, have invented certain new and useful Improvements in Nonsaturating Induction Relays, of which the following is a specification.

My improvements relate generally to electrical apparatus in which a plate of conducting material is moved by electromagnetic action thereon produced by an alternating magnetic flux. I have shown and described these improvements as embodied in an inverse time limit overload relay of the induction type which employs a shaded pole electromagnet for rotating a disk of conducting material.

One of the objects of my invention is to so design or adjust devices in which a plate is electromagnetically moved, particularly inverse time limit devices, as to impart thereto a desired characteristic. For example, I may by means of this invention impart a desired form and position to the time-current curve of an inverse time limit overload relay in the manufacture of the device, or in the course of the use thereof.

Another object is to improve the action of such devices and particularly to compensate in a new manner, for a varying torque exerted on the rotating disk such as the varying counter torque exerted when the disk in turning winds up a spring.

A still further object is to simplify and cheapen the construction, particularly by dispensing with magnetic saturation and features which have been commonly employed to secure a usable characteristic or curve by means of magnetic saturation.

Another object is to secure adaptability of the same device to currents of different orders of magnitude.

Other objects will be apparent from the following detailed description and explanation.

In the accompanying drawing the improvements which constitute my invention are shown embodied in an inverse time limit overload relay of the induction type employing a shaded pole magnet to rotate a disk of conducting material. Such relays as is well understood in the art are used to pro-

tect electrical lines and apparatus against injury by the persistence for too great a time of an excessive current. A current greater than the line or apparatus is designed to bear is called an overload. A small overload may persist for a relatively long time before any damage is done. A large overload is harmful if allowed to persist for a relatively short time. Inverse time limit overload relays are intended to actuate a circuit breaker or otherwise remove the overload only after the overload has persisted for a length of time which is longer or shorter as the overload is smaller or larger. Such devices while affording protection from damage by overloads, do not interrupt the circuit when the overload is one which would not persist long enough to be harmful even if protecting devices were not used.

An example of such an inverse time limit overload relay used in the past is found in the patent to Ricketts, No. 1,286,415. That device like the relay shown in this application has a shaded pole electromagnet which rotates a copper disk against the torque of a coiled spring, and against the drag of a permanent magnet, to close a local circuit and actuate a circuit breaker. But Ricketts's device depends upon the magnetic saturation of iron to obtain the proper time of action for certain overloads. This requires special additional parts. My device does not depend upon or employ magnetic saturation of iron. In my device the proper time of action for both small and large overloads is secured entirely by other means.

Inverse time limit overload relays have also been suggested heretofore which employ a shaded pole electromagnet acting on a copper disk against an initial torque and which do not make use of the magnetic saturation of iron. For example, Patent No. 884,066 to Brown discloses a relay in which a shaded pole electromagnet rotates a copper disk against a torque produced by a weight and against the drag of a permanent magnet, and which does not appear to involve the magnetic saturation of iron. But such devices so far as I am aware have never come into use. The reason for this, I believe, is that it has been impossible to design them so that the time of action for both moderate and larger overloads will meet the

requirements of practice. In other words, the time-current curve of such devices did not conform closely enough with the time-current curve of injury through overload to make them desirable. This difficulty is overcome by my invention herein disclosed.

In the drawings accompanying and forming part of this application:

Fig. 1 is a perspective view of the essential features of an inverse time limit overload relay embodying my invention.

Fig. 2 is a diagram of the windings and connections of the electromagnet which cooperates with the conductive disk.

Fig. 3 is a diagram showing the circuits and connections for operating a circuit breaker and showing also the circuit connections between the relay and the line.

Fig. 4 is a set of curves to illustrate the principle of the invention.

Fig. 5 is a detail view of that end of the electromagnet which cooperates with the conducting disk, showing an adjustable construction of shaded pole pieces.

In the drawings, the reference character 1 designates a disk of conducting material mounted on a rotatable shaft 2. An electromagnet 3 and permanent magnets 4 and 5 are mounted so as to pass magnetic flux through the disk 1. The pinion 6 on the shaft 2 engages the gear 7 which is mounted on the rotatable shaft 8. A pin 9 mounted on the gear 7 is normally held against a back stop 10 through the action of the spring 11 on the shaft 2. The position of the back-stop 10 is adjustable by means of a lever 11^a having a pointer 12 traveling on a scale 13.

The coil 25 is energized directly or indirectly by the current in the line which is to be protected. In Fig. 3 there is shown for this purpose a transformer circuit 24 having in series therewith the secondary of a transformer 23 and the coil 25. The primary of this transformer is in the line 20 which is to be protected. The transformer should not be a saturating transformer; the currents generated in the secondary thereof may be, and preferably will be, strictly proportional to the currents in the line 20 for all loads or overloads so far as the proper operation of the relay herein disclosed is concerned.

When an overload occurs the torque produced by the shaded poles 3^a, 3^b tending to rotate the disk overcomes the counter torque of the spring 11 and the disk rotates against the counter torque of the spring 11, and against the drag of the permanent magnets 4 and 5 and against the drag of the driving magnet 3. If the overload is small the speed of the disk 1, which may be regarded as constant for any given overload, will be relatively slow. If the overload is large, the speed of the disk 1 will be relatively fast.

If the overload persists until the pin 9 actuates the contact 14, a local circuit 17 is closed to energize magnet 21 and thereby hold the contact 14 firmly against the contact 15 until the solenoid 18 has operated the circuit breaker 19 and broken the main circuit 20. When the main circuit 20 has been broken the coil 25 of the driving magnet 3 is deenergized and the disk 1, gear 7 and pin 9 are returned to their initial positions by the spring 11. The operation of the circuit breaker also breaks the local circuit 17 at 22 allowing the movable contact 14 to return to its normal position. When the circuit breaker 19 is reset to close the main circuit 20, the break in the local circuit at 22 is closed so that the local circuit is then ready to respond to the operation of the relay upon the next occurrence of an overload.

The coil 25 of the driving magnet 3 is preferably divided into sections which are provided with connections and taps as clearly indicated on the diagram, Fig. 2. In this diagram, 26 represents a central coil one end of which connects at 23^a with one end of the transformer circuit 24. Its other end is connected to the tap wire 27 and to one end of the split coil 28, 28^a. The other end of the coil 28, 28^a is connected to the tap wire 29 and to one end of the split coil 30, 30^a. The other end of the coil 30, 30^a is connected to the tap wire 31 and to one end of the split coil 32, 32^a. In like manner the connections are extended through tap wire 33, the split coil 34, 34^a, and tap wire 35. The tap wires 27, 29, 31, 33 and 35 are connected respectively to conducting bushings 36, 37, 38, 39 and 40. These bushings are spaced from the conducting tap plates 41 which is provided with openings 42, 43, 44, 45 and 46 registering with the opening in the bushing so that by means of a removable conducting pin 61 any desired tap may be electrically connected to the conducting tap plate 41. The plate 41 is connected by the wire 47 to the transformer circuit 24 at 48.

The coil 25 is thus subdivided so as to adapt the same device for use with circuits of different normal amperages. For example, the device might be designed so as to operate properly in connection with a circuit which normally carries 6 amperes when the pin 61 is inserted in the bushing 36 and only the central coil 26 is in the circuit 24, and so designed as to act properly with a 5 ampere circuit when the pin 61 is in bushing 37 and the coils 28 and 28^a are functioning in addition to the coil 26. The purpose of splitting each additional coil into two sections mounted respectively on the different sides of the coil 26 is to maintain the distance of the middle point of the effective portion of the coil from the pole 3^a unchanged by the inclusion or ex-

clusion of the various split coils in the energizing circuit 24. The importance of this is hereinafter made apparent.

The pole pieces 3^a and 3^b of the driving magnet 3 are preferably made adjustable both axially and circumferentially of their axes. This construction is clearly shown in Fig. 5 where 3^a and 3^b are the pole pieces provided with the shading coils 50^a and 50^b and held in position by means of the axially extending screws 51^a and 51^b passing through the ends of the legs of the driving magnet 3. The poles are held in desired vertical and circumferential adjustment by the set screws 52^a, 52^b, and 53. A screw 54, Fig. 1 cooperating with a gear 54' on the pole piece may be provided to facilitate the circumferential adjustment of the pole piece. While this adjusting screw and gear are shown only on the lower pole piece the upper pole piece might of course be similarly provided. While both pole pieces are shown adjustable, the adjustments of course could be provided on one only. The purpose of the circumferential adjustment of the shaded poles is to vary the torque which they produce tending to turn the disk 1. The force which they exert tending to turn the disk may be varied from zero to a maximum by changing the direction of their pull from a direction radially of the disk 1 to a direction circumferentially thereof.

The disk 1 is provided with a series of serrations or notches 55 of varying depth in its circumference. Such serrations adjacent the shaded poles increase the resistance to the eddy currents generated by the shaded poles in the disk and thus lessen the pull tending to turn the disk; the deeper the serrations, the less the pull. By having the serrations deepest at that part of the circumference of the disk which is adjacent the shaded poles when the disk is in its normal or initial position, and graduated in depth so that when the disk rotates the serrations passing adjacent the shaded poles become shallower and shallower, the pull of the shaded poles tending to rotate the disk becomes greater as the disk rotates though the overload which causes the rotation remains constant. The purpose of this is to offset the increasing counter torque exerted by the spring 11 as the rotation of the disk progresses. The depth of the serrations will therefore be graded inversely in accordance with the variation in the pull of the spring 11.

At the point 60 on the circumference of the disk 1 which is adjacent the shaded poles when the disk is nearly at the end of its journey and about to press the contact 14 against the contact 15, the serrations suddenly terminate. This gives a sudden increase in the next torque turning the disk and causes contacts 14 to be closed on contact

15 with a kick. The same result may be secured by continuing the serrations past the point 60 but reducing the depth of successive serrations at the point 60 at a more rapid rate at that point than elsewhere.

70

The time lever 11^a controls the position of the back stop 10 which cooperates with the pin 9 to determine the initial position of the disk 1. By moving the lever 11^a over the scale 12, the distance through which the disk 1 must move in order to actuate the contacts 14 can be varied and the time of operation correspondingly varied. This device is particularly useful in my relay where it is desired to insure that a number of relays on the same line shall operate in a certain order.

75

I have discovered that if a disk relay operated by an alternating electromagnetic flux is so constructed that a substantial leakage of the electromagnetic flux of the driving magnet cuts the disk, an increase in the time of action is secured which is large for large overloads and small for small overloads, as compared with the increase in the time of action which may be secured by increasing the strength of the permanent magnet. This difference in the action of the permanent magnetic flux and the electromagnetic leakage flux is due to the following facts. The retarding torque of the permanent magnet varies with the speed of the disk but is independent of the strength of the current which actuates the relay. The electromagnetic flux cutting the disk, both polar and leakage, produces a retarding torque which varies with the speed of the disk and also as the square of the actuating current. The polar portion of the electromagnetic flux also produces the torque which turns the disk, but the leakage portion in the main acts only as a drag.

80

The effect of substituting to a greater or less extent a leakage of the electromagnetic flux for the flux of the permanent magnet to keep down the speed of the disk, other things being maintained the same, is to increase the time of action of the relay for large overloads and to decrease it for small overloads. In other words, the time-current curve is lifted and made flatter for large overloads and is lowered for small overloads and is given a sharper curvature between certain moderate overload values.

85

Another striking result of employing a leakage of the electromagnetic flux to retard the motion of the disk is that the time can be made to approach any definite value as desired, within reasonable limits, when the magnitude of the current is increased without limit. Expressed in the terms of mathematics, the greater the effective strength of the electromagnetic leakage flux cutting the disk, the greater will be the time of action of the relay when the current is

90

95

100

105

110

115

120

125

130

infinite. Different values of the disk-cutting electromagnetic leakage flux give time-current curves having different asymptotes at their high current ends. The greater the 5 value of this flux, the further will be the position of the asymptote from the current axis.

These results are strikingly different from those that are obtained where different effective strengths of a permanent magnet are solely depended upon to secure different time-current curves. In the latter case these 10 curves all approach the same time value when the current value is increased without limit. In other words, when different strengths of a permanent magnet are solely relied upon to secure different curves, all 15 the curves will have the same asymptote at their high current ends and the value of the 20 time of action of the relay for infinite current will be the same for all strengths of the permanent magnet.

The curves in Fig. 4 though not made from any particular tests and not to scale 25 illustrate the effects which pertain to the use of a leakage of the flux of the driving magnet cutting the disk to oppose the motion of the disk. Dotted curves A and B may be 30 taken to represent the time-current characteristics of two relays in which there is no substantial amount of electromagnetic leakage cutting the disk, curve A being secured by using a weak permanent magnet and curve B by using a strong permanent magnet. Solid curves C, D and E will then 35 represent time-current characteristics which can be secured by employing a disk-cutting leakage of the electromagnetic flux of the driving magnet. Curve C is such a curve as 40 could be obtained by means of a certain amount of such a flux in a relay which has the same weak permanent magnet as the relay of curve A. It will be noted that the 45 time of action at the high overload end of the curves is as great in curve C as in curve B but that for moderate overloads the time of action is much less in curve C than in curve B. Curve D is such a curve as could 50 be obtained by using a disk-cutting electromagnetic leakage flux in a relay which has the same strong permanent magnet as the relay of curve B. It will be noted that the time of action at high overload is much 55 larger on curve D than on curve B, but that for moderate overloads there is no such difference between the curves D and B as there is between curves B and A. An indefinite 60 number of different curves can be secured lying between the curves A and D by varying the disk-cutting electromagnetic leakage flux and the strength of the permanent magnet between the values which gave curves A and D. Curve E is an example of such a curve.

65 The general principles for thus control-

ling the shape and position of the curve are (1) that a change in the disk-cutting electromagnetic leakage flux effects a substantial change in the time of action even for the most excessive overloads, (2) that any 70 change in the disk-cutting electromagnetic leakage flux effects approximately the same change in the time of action for moderate overloads as for large overloads, (3) that changes in the effective strength of the permanent magnet are of practically no effect 75 on the time of action for extremely large overloads, and (4) that changes in the effective strength of the permanent magnet cause much larger changes in the time of 80 action for moderate overloads than for large overloads.

In general, the curves characterizing relays in which the time of action is more or less dependent on a leakage of electromagnetic flux cutting the disk, conform more closely to the time-current curves of injury by overload than do the curves of relays in which the permanent magnet is principally depended upon. And by varying the 90 amount of the electromagnetic leakage flux cutting the disk and the effective strength of the permanent magnet, the shape of the 95 curve can be controlled and given a wide variety of forms to suit special conditions to an extent that so far as I know was not before possible in relays which did not employ magnetic saturation. This proper shaping of the characteristic curve is very important where several relays are to be 100 used upon the same line or network for the purpose of segregating that section of the system in which an overload originates without interfering with the service throughout the rest of the system. 105

In order to cause the disk 1 to be cut by a substantial leakage of the electromagnetic flux from the magnet 3, the legs of this magnet may be extended across a chord of the disk as shown in Fig. 1. The amount 110 of the leakage flux may be controlled by placing the center point of the coil 25 nearer or farther from the pole 3^a. The more remote the coil is from the pole, the greater the leakage. The leakage may also 115 be controlled by varying the cross-section of the iron core of the coil 25; the smaller the cross-section of this core, the greater the leakage. This does not mean that the core 120 becomes saturated, or approximates saturation. The amount of leakage increases upon a decrease in the cross-section of the core for all substantial flux values while the variation of the flux is in proportion to the variation of the current in the energizing coil. The amount of the electromagnetic flux cutting the disk can also be 125 varied, of course, by changing the extent to which the legs of the electromagnet project over the disk. Moreover any changes in the 130

distance from the center of the disk to the point of application of disk-cutting electromagnetic leakage flux has the same effect as a change in the amount of the flux. An 5 increase in the distance from the center serves the same purpose as an increase in the amount of this flux.

While I now regard the use of a leakage 10 of the electromagnetic flux cutting the disk, either alone or in connection with a permanent magnet, as the best means of obtaining a proper form for the time current curve, a like control of the shape of this curve to that which has been hereinabove explained can be secured by adjusting the shaded 15 poles 3^a, 3^b, about their axes, so as to reduce the pull which they exert circumferentially on the disk 1 without reducing the drag of the electromagnetic flux upon the 20 disk. A like control can also be had by varying the resistance of the shading coil, or otherwise lessening its effectiveness. Each of these changes has the same effect 25 upon the characteristic curve as the provision of a leakage of electromagnetic flux cutting the disk.

In fact a like control may be had by any means which substantially increases the 30 ratio of the torque of the electromagnetic drag at unit angular velocity of the disk, to the electromagnetic torque which maintains 35 the disk at that velocity, over the value of this ratio when the electromagnetic flux which is producing drag is also fully effective in producing disk-advancing torque.

This may be more simply stated by the 40 adoption of a convention. In the rotation of conducting disks by shaded pole magnets in the prior art the sole purpose desired of the shaded pole magnet was in general to 45 rotate the disk. The forward torque of the electromagnet was all that was wanted thereof. The electromagnetic flux cutting the moving disk necessarily produced a 50 counter torque but this was not wanted. The electromagnets were therefore in general so designed as to get the maximum forward torque. The electromagnetic flux passing through the disk was concentrated 55 as much as possible and applied as far as possible from the center of the disk. Leakage flux was not passed through the disk. The shaded pole was designed for maximum efficiency in the production of forward 60 torque and so placed that its pull was directly circumferential of the disk and as far from the center as practicable. Though the counter torque was not desired, the compact application of the disk-cutting flux at the 65 outer edge of the disk also caused this disk-cutting flux to exert as much counter torque as that amount of disk-cutting flux was capable of exerting. Fig. 1 of the 70 patent to Brown to which attention has

already been called herein is a good example 65 of such a shaded pole magnet designed to fully develop its possibilities for producing forward torque and incidentally developing as much counter torque as the amount of flux which it passes through the disk is capable 70 of developing. Let us regard such a device as fully developing both the forward and counter torque capability of that particular amount of electromagnetic flux which it causes to cut the disk at any time. 75

Now if the design is such that the forward torque capability of the total electromagnetic flux cutting the disk is not fully developed and the counter torque capability 80 is fully developed the special time current characteristics hereinabove described are secured. An example of this is where part of the cutting flux is a leakage flux which is so far from the shading coil that it is not 85 fully effective in the production of forward torque. This result will be secured likewise if neither the forward torque capability nor the counter torque capability of the cutting flux is fully developed but the counter torque capability is more fully developed 90

than the forward torque capability. An example of this would be where the shaded pole was some distance in from the edge of the disk and was turned so that its pull was partly radial. The same result would also be secured if some means were devised for increasing the counter torque of the cutting electromagnetic flux beyond the value which it has in such devices as Fig. 1 of the Brown 95 patent, without also correspondingly increasing the forward torque of this flux. In general, this result is secured whenever the counter torque capability of the total electromagnetic flux cutting the disk is more 100 fully developed than the forward torque capability thereof, the full development of these torques of which this flux is capable being understood to mean that development found in such a device as that of Fig. 1 of Brown Patent, No. 884,066 as has been hereinabove explained. 105

To get a very high value of the ratio of counter torque to forward torque, two or more of the means hereinabove referred to for this purpose or other means may be adopted in the same device. For instance, the legs of the electromagnet may be placed along a chord of the disk, the cross section of the core made small, and the coil located well back from the pole, all to secure a large leakage flux cutting the disk and thereby develop a large counter torque without correspondingly developing the forward torque capability of the cutting flux, and in addition the shading coil may be made of comparatively high resistance, and made to encircle but a small portion of the pole, and be so located circumferentially of the pole 110 115 120 125

that its pull is largely radial, all of which lessen the forward torque without reducing the counter torque.

- If in the course of the design of a relay
- 5 a change is made in the ratio of the electromagnetic counter torque to the electromagnetic forward torque, by changing only the amount of the electromagnetic drag or the distance of its point of application from
- 10 the center of the disk, the effect of the permanent magnet upon the characteristic curve of the relay is not substantially changed. But if the change in the ratio of the torque of the electromagnet drag to the motion producing torque is made by changing the motion producing torque, the effect of the permanent magnet upon the characteristic curve is altered. A decrease in the motion producing torque with the attendant decrease in
- 20 the strength of the spring necessary to maintain the pick-up point at the same current value, will increase the effect of the permanent magnet so that if it is desired to leave the effect of the permanent magnet unchanged a weaker permanent magnet must be used or its effectiveness otherwise diminished.

The improvements hereinabove set forth specifically in connection with an inverse time-limit relay may obviously be applied to the control of the speed of rotation of the disk in devices other than relays. And the invention in its broadest aspect is not limited to disks or to rotating members but

30 may be applied to movable members which move in straight lines or on arcs of curves. Therefore while I have shown and described the various features of my invention embodied in one specific form of electrical instrument, I do not wish to be restricted in the protection of my invention except as required by the prior art and by the limitations of the claims.

What I claim as new and desire to secure

40 by Letters Patent of the United States, is:

1. An electrical device comprising a movable member of conducting material, a non-saturating electromagnetic means which sends alternating electromagnetic flux
- 50 through the movable member, said electromagnetic means having a pole with a shading coil thereon, the flux through the shaded pole constituting the main cause of the advance of the movable member, and means
- 55 whereby a portion of the electromagnetic flux sent through the movable member by the electromagnetic means does not pass through the shaded pole and is of relatively little effect in causing the advance of the
- 60 movable member.

2. An electrical device having in combination a rotatable disk of conducting material, a non-saturating electromagnetic means comprising a shaded pole electromagnet which sends an alternating electro-

magnetic flux through said disk, the flux through the shaded pole or poles constituting the main cause of the advance of the disk, said electromagnet extending across the disk so that a substantial leakage flux

70 cuts the disk, said leakage flux being of relatively little effect in causing the advance of the disk, and means additional to the electromagnetic fluxes for opposing the advance of the disk.

75

3. An inverse time limit device having in combination a movable member of conducting material, non-saturating means comprising a shaded pole electromagnet for advancing said movable member, said electromagnet extending across the movable member so that a substantial leakage flux cuts the movable member.

80

4. An inverse time limit device having in combination a rotatable disk of conducting material, non-saturating means comprising a shaded pole electromagnet for effecting forward rotation of the disk, said electromagnet extending across the disk so that a substantial leakage flux cuts the disk, the energizing coil of said electromagnet being spaced from the adjacent pole so as to promote leakage cutting the disk and means additional to the electromagnetic fluxes for opposing the forward motion of the disk.

85

5. An inverse time limit overload relay comprising in combination a rotatable conducting disk, non-saturating electromagnetic means comprising an electromagnet which has a shaded pole for rotating the disk, said electromagnet extending across the disk so that a substantial leakage flux cuts the disk, the energizing coil of said electromagnet being spaced from the adjacent pole so as to promote leakage cutting the disk, a permanent magnet also cooperating with said disk and means biasing the disk to initial position.

90

6. An inverse time limit device having in combination a rotatable disk of conducting material, an alternating current electromagnet embracing the disk with its poles near one edge of the disk and its legs extending across the disk, an energizing coil therefor, one of the poles being rotatable about an axis perpendicular to the plane of the disk, shading coils on the poles, a permanent magnet also embracing the disk, means for holding the disk at rest when the current in the energizing coil is below a predetermined value, the energizing coil being spaced from the adjacent pole or poles so as to cause a leakage of electromagnetic flux which cuts the disk but does not pass through the poles.

100

7. An electrical device having a movable member whose speed changes with changes in an actuating current, a shaded pole electromagnet for sending an alternating magnetic flux therethrough which causes the

105

110

115

120

125

130

- forward motion thereof and also produces a retarding pull thereon, the flux through the shaded pole constituting the main cause of the advance of the movable member, the 5 shading coil being such that its tendency to move the movable member is less than that which could be produced by a shading coil with the same amount of alternating magnetic flux passing through the shaded pole 10 and movable member, and means additional to the electromagnetic flux for opposing the forward motion of the movable member.
8. An inverse time limit device having in combination a rotatable disk of conducting material, a shaded pole electromagnet adapted to send an alternating magnetic flux through said disk which causes the rotation thereof and also produces a retarding drag thereon, the position of the shading coil 15 being such as to diminish the torque thereof tending to rotate the disk without correspondingly reducing the counter torque of the electromagnetic flux upon the disk.
9. An inverse time limit device having 20 in combination a rotatable disk of conducting material, a shaded pole electromagnet adapted to send an alternating magnetic flux through said disk which causes the rotation of the disk and also produces a retarding drag thereon, the position of the shading coil circumferentially of the pole being such that the pull of the disk caused by the shading coil is at an angle to the line of motion of the disk past the shaded pole, a permanent magnet embracing the disk and means 25 biasing the disk toward its initial position.
10. An electrical device having in combination a movable member of conducting material, an electromagnetic means to send a shifting alternating magnetic flux through the movable member and give the same its forward motion, means for adjusting the strength of the pull of the electromagnetic means which gives the movable member its 30 forward motion without substantially varying the drag which the electromagnetic means exerts on the movable member when the latter is in motion at a given speed and means additional to the electromagnetic 35 fluxes for opposing the forward motion of the movable member.
11. An inverse time limit device having in combination a rotatable conducting disk, a shaded pole electromagnet sending an 40 alternating magnetic flux through said disk to rotate it, a pole of the magnet with a shading coil thereon being adjustable about an axis perpendicular to the disk.
12. An electrical device comprising a movable member of conducting material whose 45 speed changes with changes in an actuating current, non-saturating means for passing a varying magnetic flux therethrough to produce an advancing tendency which varies 50 with the strength of the varying magnetic
- flux passing through the movable member and causes its forward motion, and a retarding tendency which varies with the strength of said magnetic flux and with the speed of the movable member, the capability of the 70 varying magnetic flux which passes through the movable member for producing the retarding tendency being more fully developed than its capability for producing the advancing tendency. 75
13. A rotatable disk of conducting material, a non-saturating electromagnetic means comprising a shaded pole electromagnet for passing a magnetic flux through said disk to produce the forward torque 80 which causes the same to move and a retarding effect thereon which is proportional to its speed, the capability of the electromagnetic flux passing through the disk for producing counter torque being more fully 85 developed than its capability for producing forward torque and means additional to the electromagnetic flux for opposing the forward motion of the disk.
14. An inverse time limit device having 90 in combination a rotatable conducting disk, a non-saturating electromagnetic means comprising a shaded pole electromagnet for sending an alternating magnetic flux through said disk which produces thereon the forward torque which gives the disk its motion and also a counter torque thereon which is proportional to the speed of the disk, the capability of the alternating magnetic flux passing through the disk for 95 producing counter torque being more fully developed than its capability for producing forward torque, a permanent magnet also sending flux through said disk and means 100 biasing said disk to its initial position. 105
15. A time limit overload device having in combination a movable member of conducting material and a non-saturating electromagnetic means sending an alternating magnetic flux through the movable member to produce a pulling action on the movable member to move it and a retarding action which varies with the velocity thereof, the retarding action of the alternating magnetic flux sent through the movable member, being proportioned to the pulling action thereof to obtain a relation between the speed of the movable member and the size of the overload which conforms to the 110 relation between the period of safe duration of the overload and the size of the overload. 115
16. A time limit overload device having in combination a rotatable conducting disk which operates protective apparatus upon movement through a predetermined arc, a non-saturating electromagnetic means comprising a shaded pole electromagnet for sending an alternating magnetic flux 120 through the disk to produce the forward 125

- torque which rotates the disk and also a counter torque which is proportional to the speed of the disk, a permanent magnet also sending magnetic flux through the disk, and 5 means biasing the disk to its initial position, the counter torque of the electromagnetic means and the drag of the permanent magnet being proportioned to the forward torque of the electromagnet to obtain a relation 10 between the time of action of the relay and the size of the overload which conforms to the relation between the period of safe duration of overload and the size of the overload.
- 15 17. A movable member of conducting material, an electromagnet which operates the movable member and also produces a drag thereon which is proportional to the speed of the movable member, a leg of the electromagnet extending over the movable member, an exciting coil on said leg, said coil being subdivided into a central coil and pairs of coils, one coil of each pair being on one side 20 of said central coil and the other coil of each pair being on the other side of said central coil.
18. An inverse time limit device comprising a movable member of conducting material, a shaded pole electromagnet which sends an alternating magnetic flux through the movable member to cause its motion and also exert an opposition to the motion of the movable member which is proportional to the speed of the movable member, a leg of the electromagnet extending over said movable member, an exciting coil, said coil been subdivided into a central coil and pairs of coils, one coil of each pair being on one side of said central coil and the other coil of each pair being on the other side of said central coil, and taps these coils and connections so that current may be sent at will through the central coil or through the central coil and any desired number of the coils on each side thereof. 40

In witness whereof, I have hereunto set my hand this 20th day of January, 1923.

CHESTER I. HALL.
